Primary Examiner — Cathron C Brooks*Assistant Examiner* — Christian P. McLean(74) *Attorney, Agent, or Firm* — Boyle Fredrickson, S.C.(57) **CLAIM**

The ornamental design for an open sign, as shown and described.

DESCRIPTION

FIG. 1 is an isometric view of a first embodiment of an open sign incorporating my new design, wherein the portions shown in phantom form no part of the claimed design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

The broken lines illustrate portions of the open sign that form no part of the claimed design.

1 Claim, 5 Drawing Sheets(56)
